UNITED STATES PATENT OFFICE.

CHARLES R. STEVENSON, OF MISHAWAKA, INDIANA, ASSIGNOR TO NATIONAL VENEER PRODUCTS COMPANY, OF MISHAWAKA, INDIANA, A CORPORATION OF INDIANA.

GOLF-BAG.

1,254,640.

Specification of Letters Patent. Patented Jan. 22, 1918.

Application filed March 7, 1913. Serial No. 752,574.

To all whom it may concern:

Be it known that I, CHARLES R. STEVENSON, a citizen of the United States, residing at Mishawaka, in the county of St. Joseph and State of Indiana, have invented certain new and useful Improvements in Golf-Bags, of which the following is a specification.

The principal object of my invention is to provide a new and improved golf bag so constructed as to be especially durable and serviceable. Another object of my invention is to provide a new and improved construction for the lower end of the golf bag by which it is reinforced with a rawhide member so as to withstand wear by being dragged along the ground and otherwise. These and other objects of my invention will be made apparent in the following specification taken with the accompanying drawings.

For the purpose of illustrating and explaining my invention I have shown one specific embodiment thereof, together with considerable detail, in the accompanying drawings. It will be understood that the invention is defined in the appended claims.

Referring to the drawings—

Figure 1 is a general perspective view of my improved golf bag.

Fig. 2 is an elevation of the lower end thereof, certain parts being broken away to show the construction more fully.

Fig. 3 is a fragmental section across the lower end of the golf bag; and

Fig. 4 is a longitudinal section of the upper and lower ends of the golf bag.

The side wall 10 of flexible material, such as heavy canvas, has a number of longitudinal leather stays 11 sewed thereto, and at an early stage in the manufacture of the bag the leather strap 12 is sewed on, to which is attached the handle 13: the pocket 14 for golf balls is also attached to the side wall.

The stay rods 15 are next inserted under the longitudinal leather stays 11. Each stay rod has its ends bent to form upper eyes 16 and lower eyes 17. After the parts have been assembled to the extent just stated the leather cuff 18 is sewed along the lower edge of the side wall 10, the stitches being indicated as 19 in the drawings. In making the stitches the thread is jumped over the stay rods,—in other words, an extra long stitch is taken to carry the threads over each rod 15. Next the rivets 20 are applied, pass-

ing through the cuff 18, the leather stay 11, the lower eye 17, and clenching within the body wall 10.

The meeting edges of the body wall are reinforced by leather strips, as designated in Figs. 2 and 4. After the various parts have been attached to the body wall 10, as stated in the foregoing part of the specification, the edges 21 are brought together and secured by the lacing 22.

An iron ring 23 is placed around the upper end of the bag and a leather member 24 is doubled down over the ring 23 on the inside and outside of the side wall. These parts are secured in the relation just stated by the lacing 25, and, further by rivets 26 which go through the upper eyes 16 in the stay rods 15. The shoulder strap 27 engages the ring 23 at one end and is fastened to the strap 12 at the other end.

The disk-shaped bottom member 29, consisting of a three-ply veneered board with inside and outside leather facings is slipped within the lower end of the body wall 10. A rawhide member 30, previously shaped on a wooden block so as to have the form shown in Fig. 1, is then applied. This rawhide member is generally circular in form and has one flange directed to surround the lower edge of the cuff 18 and the other flange adapted to extend inwardly under the bottom member 29. This part of the rawhide member 30 is secured to the bottom member 29 by rivets 31, and the other edge of the rawhide member is secured to the cuff by stitching 32.

A bottom clamp 33 of brass is applied over the meeting ends of the rawhide member and is fastened to the cuff by means of rivets 35 and to the bottom 29 by rivets 34. This metal clamp is diametrically opposite to the handle 13 and shoulder strap 27.

The rawhide member 30 receives the wear to which the bag is subjected when it is dragged along the ground. The clamp 33, being opposite the handle 13 and shoulder strap 27, receives the greatest amount of wear coming on this side. The general combination among the various parts, the stay rods, the solid bottom 29, the leather cuff 18, and the rawhide reinforcing member 30, all contribute to make a very strong and durable golf bag.

I claim:

1. In a golf bag, a flexible side wall, a

rigid bottom, leather stays along the side wall, metal stay rods within said leather stays, said metal stay rods having their ends formed to make eyes, a cuff around the lower 5 end of the side wall, rivets through said cuff and through the adjacent eyes of the stay rods, and a rawhide reinforcing member having a portion thereof around the said cuff over the heads of said rivets and another portion extending under said rigid 10 bottom.

2. In a golf bag, a flexible side wall, a rigid bottom, leather stays along the side wall, metal stay rods within said leather 15 stays, a cuff around the lower end of said side wall, and rivets through said cuff and said stay rods.

3. In a golf bag, a flexible side wall, longitudinal leather stays attached thereto, 20 metal stay rods within said leather stays having eyes at their ends, a metal ring

around the upper end of the golf bag, a leather member embracing said ring and having its edges lapping inside and outside of the side wall, and rivets through said 25 leather member and through the adjacent eyes of the metal stay rods.

4. A golf bag, comprising a side wall 10, a handle 13 secured thereto, the leather cuff 18 around the outside of said wall at the 30 bottom thereof, the rigid bottom 29, the rawhide reinforcing member 30 secured to said rigid bottom and to said cuff and side wall, and a metal clamp 33 over the meeting edges of said rawhide member on the side of 35 said bag opposite said handle.

In testimony whereof, I have subscribed my name.

CHARLES R. STEVENSON.
